SCISSORS WITH FORCE MULTIPLIERS

Petros Zougas, Toronto, Ontario, Canada, assignor of a fractional part interest to Sokratis Romas, Toronto, Ontario, Canada

Filed Apr. 14, 1971, Ser. No. 134,113

Term of patent 14 years

Int. Cl. D8—03

U.S. Cl. D8—61

FIG. 1

FIG. 2

FIG. 3

FIG. 4

FIG. 5

FIG. 1 is a rear elevational view of a scissors with force multipliers, showing my new design;

FIG. 2 is a top plan view;

FIG. 3 is a front, top and side perspective view with the force multiplier lever and blades in the open position;

FIG. 4 is a side elevational view with the force multiplier lever and blades in closed and locked position, and

FIG. 5 is an opposite side elevational view with the force multiplier lever and blades in closed and locked position.

I claim:

The ornamental design for a scissors with force multipliers, as shown.
